[57] CLAIM

The ornamental design for a window latch, as shown and described.

DESCRIPTION

FIG. 1 is a top, front, and left side perspective view of a window latch showing my new design;
FIG. 2 is an enlarged top plan view thereof;
FIG. 3 is an enlarged left side elevational view thereof;
FIG. 4 is an enlarged front elevational view thereof, the rear being plain and unornamented;
FIG. 5 is an enlarged right side elevational view thereof; and,
FIG. 6 is an enlarged bottom plan view thereof.
The broken-line depiction of a fragment of a window in the views is for illustrative purposes only and forms no part of the claimed design.
